INVENTOR.

Orrin Thompson,
BY
Geo. P. Kimmel
ATTORNEY.

UNITED STATES PATENT OFFICE.

ORRIN THOMPSON, OF NEENAH, WISCONSIN

BATHTUB.

Application filed February 23, 1928. Serial No. 256,356.

This invention relates to bath tubs, and has for one of its objects to provide in a manner as hereinafter set forth a tub of such class, having means in convenient reach of 5 the bather to be gripped by the hands for supporting the occupant from slipping during the period of entering or leaving the tub, and furthermore is adapted to aid the occupant in raising or lowering the body to a 10 sitting position.

Another object of the invention is to provide, in a manner as hereinafter set forth, a bathtub having one or more of its walls provided with integral means arranged relative to the wall to constitute a hand rail so disposed to prevent crushing of the hand when the rail is gripped by the occupant. 15

Further objects of the invention are to provide, in a manner as set forth, a tub 20 with means aforesaid in its wall, which is efficient in its intended use, without detracting from the appearance of the tub, strong, durable and compact, simple in its construction and arrangement and comparatively inexpensive to prepare. 25

With the foregoing and other objects in view, the invention consists of a novel construction, combination and arrangement of parts as hereinafter described and illustrated 30 in the accompanying drawings, wherein is shown an embodiment of the invention, but it is to be understood that changes, variations and modifications may be resorted to which fall within the scope of the invention as 35 claimed.

In the accompanying drawings wherein like reference characters denote corresponding parts throughout the several views:—

Figure 1 is a fragmentary view in elevation and partly in section, of a bath tub in accordance with this invention. 40

Figure 2 is a top plan view thereof.

Figure 3 is a section on line 3—3 of Figure 1.

In the accompanying drawings the tub is 45 designated generally at 1 and has the usual side and end walls and a bottom. One or more walls preferably one side wall has the upper inner corner thereof cut away for an appropriate length to provide a recess or cavity 2 extending lengthwise of the tub. The cavity 2 includes a pair of end walls 3, 4 and an upstanding bottom or inner wall designated generally at 5, of concavo-convex contour, with the convex portions indicated at 50 6, 7 and the concave portion at 8. The cavity 55 opens at the inner part of the top edge 9 of

the side wall of the tub and at the upper portion of the inner face 10 of that side wall in which the cavity is formed. The concave part 8 of the bottom or inner wall 5 is disposed centrally of the latter, and intermediate the convex parts 6, 7 which are located at the upper and lower margins of the upstanding bottom wall 5. 60

Extending longitudinally of the cavity 2, 65 and from one end wall 4 to the other end wall 5 is a cylindrical rail 11 made integral with the said side wall of the tub. The rail 11 is arranged in spaced relation to the bottom or inner wall of the recess 2, opposes 70 concave portion 8, is positioned below the top edge 9 and is flush with the inner face 10 of the side wall of the tub. The rail 11 being opposed to concave portion 8 is therefore spaced with respect to the convex portions 6 and 7. It will be apparent to those skilled in the art that the bathtub referred 75 to herein is of that type or character designated by the plumbing trade generally as porcelain, vitreous enamel and the like. 80

As is common in the trade a shell or form of the article is made out of metal and can be cast or stamped. The shell or form is covered with a composition and processed in various ways to give the finished article a hard 85 surface resembling stone or glass. In the construction of the shell according to my invention, the cavity 2 may be cast or stamped in the shell. The end walls 3, 4, of said cavity may be cast or stamped with an opening 90 to accommodate the rail 11 to be inserted thereafter, or the rail may be cast or stamped integral therewith. In either event the covering composition is applied to the preformed shell and processed, so as to make the rail 95 integral with the finished tub.

What I claim is:—

A bathtub having one of its walls provided lengthwise of its top edge with a cavity having a pair of end walls and an inner wall formed with a concave portion, said cavity opening at the top edge and inner face of the tub wall, and a hand rail having its ends integral with said end walls and being free of connection to and further spaced from 100 said inner wall, said rail opposing said concave portion, positioned below said top edge and having its outer side flush with the inner face of the tub wall. 105

In testimony whereof I affix my signature 110 hereto.

ORRIN THOMPSON.
